SWEETENING PROCESS

James W. Ryder, Watchung, N. J., assignor to
 Standard Oil Development Company, a corporation of Delaware

Application March 11, 1949, Serial No. 80,859

6 Claims. (Cl. 196—32)

1
 The present invention is concerned with an improved sweetening process. The invention is more particularly concerned with the removal of mercaptan compounds, especially those mercaptan compounds which have heretofore been relatively difficult to remove from hydrocarbon fractions, which fractions boil in the motor fuel, kerosene, diesel oil and heating oil boiling ranges. In accordance with the present invention a feed hydrocarbon fraction which is characterized by containing mercaptan compounds is contacted with a relatively strong caustic solution which contains an alkyl phenolate and an aromatic mercaptide. By treating a mercaptan containing feed oil with a treating solution of this character, unexpected and desirable results are secured with respect to the removal of the mercaptan compounds from the feed oil.

It is well known in the art to treat petroleum oils by various procedures in order to remove objectionable compounds, as for example sulfur compounds therefrom. For example, it is known to treat petroleum fractions boiling in the motor fuel boiling range and in the general range below about 700° F. with various chemical reagents such as, sodium or potassium hydroxide solutions. Also, it has long been known that weakly acidic materials, such as mercaptans, are reactive to various degrees with basic materials. One method for the removal of mercaptan compounds from hydrocarbon streams containing the same has been to treat these streams with a reagent which is insoluble in the hydrocarbon stream but which contains alkali type of material which reacts with the mercaptan constituents. Such treating agents have normally been aqueous solutions of an alkali material. The reaction product between the treating solution and the mercaptan is a basic salt of the mercaptan. Normally, such salts exhibit some solubility in the aqueous phase. However, this solubility decreases as the molecular weight or branchiness of the hydrocarbon structure of the mercaptan increases. Therefore, caustic solutions when they are only spent to a small extent in mercaptide salts will not give any further reduction in mercaptan content despite the fact that these treating solutions have a large residual free caustic content. The art has also recognized that the efficiency of the spent caustic can be partially or fully restored by regeneration of these solutions. The regeneration normally consists of removal of a part or all of the mercaptide salts by means of hydrolysis and vaporization or by oxidation.

One method is to employ steam regeneration

2
 for the revivification of caustic solution spent in mercaptan removal from hydrocarbon streams. The steam regeneration is normally carried out in a packed tower or a tower provided with bubble plates or pierced type tray plate design. The steam hydrolyzes the mercaptide salts to the corresponding mercaptans which are stripped out by the steam vapors and taken overhead. The regenerator also serves as a means of adjusting the gravity of the caustic solution, which has been shown to be critical. The regenerated caustic is withdrawn from the bottom of the regeneration tower and reused in the extraction stage of the system wherein the caustic contacts the hydrocarbon stream through suitable mixing devices for further extraction of mercaptans by the same caustic.

It has also been found that certain constituents of the oil itself will function as solubility enhancing agents. These constituents tend to improve the partition coefficient of the acid mercaptan in the aqueous phase and to increase the solubility of the mercaptide salts in the aqueous phase, particularly when the mercaptan is of a relatively high molecular weight. As mentioned, mercaptans are difficult to extract from hydrocarbon solutions by straight aqueous alkali solutions. This is particularly true of the higher molecular weight mercaptans. In general, this is occasioned by the fact that the two phases are not miscible and that good contact must be obtained to allow the alkali metal ion to react with the mercaptan hydrocarbon. Furthermore, once the reaction has occurred, it is essential that if the extraction of the mercaptan is to be accomplished the reaction product must be soluble in the aqueous layer. As pointed out heretofore, the higher the molecular weight of the mercaptan the lower the solubility of the corresponding mercaptide salt in the aqueous phase. The solubility enhancing agents tend to increase this solubility and thus increase the effectiveness of the alkali treating solution.

The exact chemical nature of these solubility enhancing agents is not entirely known. However, it is felt that they comprise the lower molecular weight aliphatic acids and the various alkyl substituted phenolic compounds. It has been found that phenolic type materials having 45 alkyl side chains containing less than about 3 carbon atoms are not effective by themselves as solubility promoters and that organic carboxylic acids having less than about 3 carbon atoms per molecule are likewise not very effective. However, 50 as the length of the side chain of the phenols in-

creases or the length of the aliphatic acid hydrocarbon chain increases, their effectiveness as solubility promoters increases greatly. However, the solubility of the acids or phenols themselves in the caustic solution decreases with increasing hydrocarbon chain length and thus limits the molecular weight of acid or phenolic type material which can be employed. It is believed that the optimum chain length should be from about 3 carbon to 7 carbon atoms for the acids.

As pointed out heretofore, alkyl substituted phenols are very desirable as solvent enhancing agents, but that as the length or number of side chains of the phenols increase, their effectiveness is impaired due to the fact that these phenols themselves lose solubility in the alkali. Furthermore, with respect to any particular alkyl phenol or class of alkyl phenols, their solubility in the alkali solution decreases as the strength of the alkali solution increases. However, it has been discovered that providing an aromatic mercaptan is utilized in conjunction with the alkyl phenol and caustic solution, the solubility of the alkyl phenol in the alkali is materially increased resulting in substantially increasing the effectiveness of the alkyl phenols as solvent enhancing agents.

Thus it has now been discovered that providing a feed oil is treated with an alkali solution containing an alkyl phenolate and an aromatic mercaptide, unexpected and desirable results are secured with respect to the removal of mercaptan constituents from the feed oil. The present invention may be readily understood by reference to the drawing illustrating one embodiment of the same.

Referring specifically to the drawing, a feed oil which for the purpose of illustration is assumed to be a fraction boiling in the motor fuel boiling range and derived by thermally cracking a gas oil is introduced into zone 15 by means of feed line 1. In zone 15 the oil is handled in a manner to free the oil of hydrogen sulphide. This may be accomplished by a washing operation with a suitable solvent, as for example caustic soda, or the removal may be accomplished by means of a distillation process. If a distillation process be utilized the hydrogen sulphide is usually removed from the propane in a stabilization and debutanization operation. Zone 15 may comprise any suitable number and arrangement of stages. If a washing solvent is utilized, it is introduced into zone 15 by means of line 5 and withdrawn from zone 15 by means of line 6. A suitable washing solvent for example comprises a weak caustic solution. The oil free of hydrogen sulphide is withdrawn from zone 15 by means of line 2 and introduced into caustic treating zone 16. In zone 16 the oil is contacted with a caustic solution which for the purpose of illustration is assumed to be a sodium hydroxide solution. Fresh caustic is introduced into zone 16 by means of lines 10 and 7. Zone 16 may comprise any suitable arrangement of treating and mixing zones. The spent caustic solution is withdrawn from zone 16 by means of line 8 and passed to regeneration zone 17 wherein the solution is handled in a manner to regenerate the same. This is usually accomplished by introducing steam into zone 17 by means of line 21 and removing overhead by means of line 11 the mercaptans. The regenerated caustic is withdrawn from the bottom of zone 17 by means of line 9 and recycled to zone 16. Spent caustic may be withdrawn from the system by means of line 22.

while fresh caustic may be added by means of line 10. Since thermally cracked petroleum oils contain alkyl phenols, it may not be necessary to add these particular constituents from an external source. However, these relatively low molecular weight phenols are not particularly effective and it is therefore desirable to add to the oil, boiling in the motor fuel boiling range, higher boiling phenolic constituents. However, since thermally cracked petroleum hydrocarbons do not contain, to any substantial extent, aromatic mercaptans, it is also necessary in accordance with the present invention to add these mercaptans to the caustic preferably by means of line 23. Thus, the treating solution comprises a caustic solution containing an alkyl phenolate and aromatic mercaptides.

The treated oil withdrawn from zone 16 by means of line 3 is passed into zone 18 wherein it is water washed in order to further refine the same. The water is introduced into zone 18 by means of line 12 and withdrawn by means of line 13. The refined oil is withdrawn from the system by means of line 4 and further handled as desired.

The invention is broadly concerned with the removal of mercaptan compounds from petroleum hydrocarbons containing the same utilizing an alkyl phenolate in conjunction with an aromatic mercaptide. By utilizing a solution of this character, the solubility of the alkyl phenol in the caustic solution, as for example, in the sodium hydroxide solution is increased. It is thus, possible to utilize a much stronger caustic solution with a resulting improved efficiency in the removal of the mercaptan compounds, particularly the higher mercaptan compounds from the oil stream.

The invention is particularly adapted for the treatment of petroleum oils boiling below about 700° F. especially those oils boiling in the motor fuel boiling range which fractions boil below about 420 F. The process however can be utilized in the treatment of diesel fuels, kerosenes, gas oils and the like. A particularly desirable hydrocarbon fraction for use in conjunction with the present invention is a fraction which has been secured by a thermal cracking operation. In these operations petroleum fractions, as for example, gas oils, reduced crudes and the like, are cracked at elevated temperatures and pressures. Pressures are in the range above about 250 lbs. per sq. in. and as high as 1000 lbs. per sq. in. Cracking temperatures are in the range above about 800° F. and are usually in the range of about 875° F. to 950° F.

These thermally cracked fractions, particularly those fractions which boil in the range from about 400° F. to 700° F. contain naturally occurring alkylated phenols and thus by adding to the caustic solution utilized an aromatic mercaptan, the desirable treating solution is secured. Furthermore, the invention may be readily adapted to the treatment of fractions secured from catalytic cracking operations. These fractions ordinarily contain aromatic mercaptans which are present as thiophenols, thiocresols or thioxyleneols, as for example, thiophenol, methyl thiophenol, dimethyl thiophenol, ethyl thiophenol, diethyl thiophenol, propyl thiophenol, and dipropyl thiophenol. However, these aromatic mercaptans are subject to an unusual phenomenon in that when oxygen is present oxidation of olefins and diolefins in the gasoline is catalyzed by the presence of these aromatic mercaptans. The olefins and diolefins are

oxidized to peroxides, which in turn destroy the aromatic mercaptans. Thus, unless special precaution is taken to exclude oxygen and thus prevent the destruction of the aromatic mercaptans, it will also be necessary to add these aromatic mercaptans to the treating solution containing the phenols if the present invention is to be carried out with respect to these particular feed oils.

The alkyl phenolate is selected from a class of alkyl phenolates which may be represented by the following formula:

in which X represents a metal selected from the group consisting of sodium, potassium, lithium, rubidium and cesium; and in which R represents hydrogen and at least one alkyl group. The alkyl group may contain from 2 to 7 carbon atoms in the group, however, it is preferred that the group comprise from about 3 to 4 carbon atoms. The number of alkyl groups on the ring likewise may vary in the range from about 1 to 4, however, it is preferred that at least one ortho position be left open. Satisfactory alkyl phenols for use in conjunction with the present invention are for example ortho, meta and para normal propyl phenol; ortho, meta and para isopropyl phenol; ortho, meta and para butyl phenol; ortho, meta and para secondary butyl phenol; para tertiary butyl phenol, para amyl phenol, para tertiary amyl phenol. Specific satisfactory compounds are for example, p-tert. butyl-m cresol, p-tert. butyl phenol, p-tert. amyl phenol, m-isopropyl-o cresol (Carvacrol) and p-tert. butyl m-ethyl phenol. A particularly desirable source of these alkylated phenols is from gas oils and heating oils which boil in the range from about 400° F. to 700° F. and which have been derived from a thermal cracking operation. A particularly desirable source of these alkylated phenols is from heating oil fractions derived from a naphthenic type crude, as for example a quirquire crude.

One method of segregating a mixture of desirable alkylated phenols is to treat a petroleum fraction boiling in the range from about 400 to 700° F. which has been secured from a thermal cracking operation with a 10° Bé. sodium hydroxide solution. After extracting the cracked gas oil, the caustic solution is segregated and then neutralized with a strong acid. The acid oils are thus sprung from the solution. These acid oils comprising alkylated phenols are particularly desirable for use in accordance with the present invention.

The aromatic mercaptides employed in the present invention are selected from the class of compounds represented by the following structural formula:

in which X represents a metal selected from the group consisting of sodium, potassium, lithium, rubidium and cesium; and in which R represents

hydrogen or an alkyl group. The alkyl group may contain from 1 to 7 carbon atoms in the group. However, it is preferred that the number of carbon atoms in the alkyl group be not greater than

5 4. The number of alkyl groups on the ring may vary in the range from 0 to 4; however, it is preferred that at least one ortho position be left open. Satisfactory aromatic mercaptans are for example, thiophenol and thiocresol. Other 10 satisfactory mercaptans are for example dimethyl thiophenol, ethyl thiophenols and propyl thiophenol. Specific satisfactory compounds are for example, thiophenol, p-thio cresol, o-thio cresol, p-ethyl thiophenol and 1 thio-2,4 methyl benzene.

15 The caustic solution used in the present invention should contain from about 10 to 30% free NaOH. A desirable caustic solution contains from about 20 to 25% free NaOH or equivalent. The amount of caustic solution used based 20 upon the feed oil being contacted is preferably from 5 to 50% by volume of caustic solution per volume of oil.

The concentration of the alkyl phenolates present in the caustic solution should preferably be 25 in the range from about 5 to 50% by weight based upon the weight of NaOH in said caustic solution. A preferred concentration is in the range from about 10 to 25% by weight. The concentration of the aromatic mercaptide present is 30 preferably in the range from about 5 to 20% by weight based upon the weight of the NaOH in said caustic solution. A preferred concentration of aromatic mercaptides is in the range from about 10 to 15% by weight based upon the caustic solution.

35 The present invention may be further illustrated by the following examples illustrating embodiments of the same.

40

Example 1

A thermally cracked naphtha boiling in the motor fuel boiling range (80° F.-420° F.) and derived from a naphthenic type crude had a copper number of 31. This naphtha was treated 45 with 15 volume per cent of a caustic solution. The caustic solution comprised 18 volume per cent of alkyl phenol, 6 volume per cent of p-thiocresol and 260 grams per liter of free NaOH.

50 The phenols were derived by treating a heating oil fraction boiling in the range from about 400° F. to 700° F. with a sodium hydroxide solution having a gravity of about 10° Bé. About 10 to 15 volume percent of the sodium hydroxide solution 55 was employed, per volume of oil contacted. The heating oil fraction was derived by a thermal cracking operation from a naphthenic type crude. The phenols were freed by acidifying the spent caustic solution. The resulting mixture of phenols comprised p-tert. butyl-m cresol; p-tert. butyl phenol; p-tert. amyl phenol; m-iso propyl-o cresol and p-tert. butyl m-ethyl phenol. The treated naphtha had a copper number less than 60 0.5 and passed the doctor test¹.

65 In another test wherein conditions were the same as described above except that the treating solution did not contain thio cresol, the treated

70 ¹The doctor test is a means of making sure that hydrocarbon fractions are free of mercaptans which render the fraction "sour." A sample of the hydrocarbon is shaken with a sodium plumbite solution and a trace of free sulfur. If after shaking, the hydrocarbon, plumbite solution, and sulfur have not changed color, mercaptans are absent, the stock is "sweet" and the doctor test is "Pass." If discoloration occurs mercaptans are present and the test does not pass ("DNP").

oil had a copper number² of 10 and did not pass the doctor test.

Example 2

In one operation a treating solution contained 280 grams of free NaOH per liter. Alkyl phenols derived from a petroleum hydrocarbon fraction, as described in Example 1, were added to this solution. Approximately 10 volume percent of alkyl phenols were dissolved. The solution was used to contact a cracked naphtha having a copper number of 35. The treated fraction had a copper number of 10 and did not pass the doctor test.

In a similar operation to that described above the concentration of the sodium hydroxide was again 280 grams per liter. Similar phenols were added except that 5.4 volume percent of p-thio cresol was also added. In this operation the caustic solution dissolved 21.4 volume percent of phenols rather than 10% as described above. When this solution was used to treat a cracked naphtha having a copper number of 35 the treated naphtha had a copper number less than 0.5 and passed the doctor test.

From the above it is apparent that the use of aromatic mercaptans increased the solubility of phenolates in the caustic solution and resulted in an improved efficiency in the removal of undesirable mercaptans from petroleum fractions containing the same.

Having described the invention it is claimed:

1. Process for the removal of mercaptan compounds from a petroleum oil which boils in the range from about 80° F. to about 420° F., which comprises treating said petroleum oil with a caustic solution containing therein an alkyl phenolate which boils above about 420° F. and an aromatic mercaptide, said alkyl phenolate having been derived from the acidification of the caustic extract of a thermally cracked stock boiling in the range of about 420° to 700° F., and said aromatic mercaptide having been derived from the caustic extract of a catalytically cracked hydrocarbon fraction.

2. Process as defined by claim 1 wherein said alkyl phenolate is selected from the class of alkyl phenolates which may be represented by the following formula:

in which X represents a metal selected from the group consisting of sodium, potassium, lithium,

²The copper number is the milligrams of mercaptan sulfur present in 100 ml. of sample under test which will react with a standard copper ammonium sulphate solution.

rubidium and cesium, and in which R represents hydrogen and at least one alkyl group, and wherein the aromatic mercaptide is selected from the class of compounds represented by the following formula:

in which X represents a metal selected from the group consisting of sodium, potassium, lithium, rubidium and cesium, and in which R represents hydrogen or an alkyl group.

3. Process as defined by claim 2 wherein said alkyl group of the phenolate contains from 3 to 4 carbon atoms in the chain.

4. Process as defined by claim 3 wherein the mercaptide contains at least one alkyl group, which group contains from 1 to 4 carbon atoms in the alkyl chain.

5. Process as defined by claim 1 wherein said caustic solution comprises a sodium hydroxide solution, the concentration of which comprises from about 10% to 30% free sodium hydroxide and wherein the concentration of the alkyl phenolate is in the range from about 5% to 50% by weight based upon the weight of the sodium hydroxide and wherein the concentration of the aromatic mercaptide is in the range from about 5% to 20% by weight based upon the weight of the sodium hydroxide present in said caustic solution.

6. Improved process for the removal of mercaptan compounds from a petroleum oil which boils in the range from about 80° to about 420° F. and which has been secured from a catalytic cracking operation which comprises contacting said oil in a manner to exclude oxygen therefrom with a caustic solution containing an alkyl phenolate which boils above about 420° F., derived from the acidification of a caustic extract of a thermally cracked hydrocarbon fraction boiling in the range of about 420° to about 700° F.
